(57) **CLAIM**

The ornamental design for an electric wheelchair, as shown and described.

DESCRIPTION

FIG. 1 is a front, top, left perspective view of an electric wheelchair showing our new design;

FIG. 2 is a rear, top, right perspective view of the electric wheelchair shown in FIG. 1;

FIG. 3 a front elevational view of the electric wheelchair shown in FIG. 1;

FIG. 4 is a rear elevational view of the electric wheelchair shown in FIG. 1;

FIG. 5 is a left-side elevational view of the electric wheelchair shown in FIG. 1;

FIG. 6 is a right-side elevational view of the electric wheelchair shown in FIG. 1;

FIG. 7 is a top plan view of the electric wheelchair shown in FIG. 1;

FIG. 8 is a top plan view of the electric wheelchair shown in FIG. 1 with the seat removed; and,

FIG. 9 is a bottom plan view of the electric wheelchair shown in FIG. 1.

The broken lines shown in the drawings represent portions of the electric wheelchair that form no part of the claimed design.
